UNITED STATES PATENT OFFICE.

JAMES V. DUNBAR, OF ELGIN, TEXAS.

RIM TOOL.

Application filed June 18, 1923. Serial No. 645,184.

The device forming the subject matter of this application is a tool, adapted to be used in correcting distorted beads on the rim of a vehicle tire, and the invention aims so to construct the tool that it may be used either to bend outwardly, a bead which has been too much bent inwardly, and, further, so to construct the tool that it may be used as a form or anvil which, in connection with a hammer 10 will bring about an inward bending of a bead which has been bent outwardly to too great an extent.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that, within the scope of what is claimed, changes in the precise embodiment of the invention shown 25 can be made without departing from the spirit of the invention.

In the accompanying drawings:

Figure 1 shows in side elevation, a device constructed in accordance with the invention, parts being broken away; Figure 2 is an elevation wherein the tool is viewed at right angles to the showing of Figure 1, parts being broken away; Figure 3 is a fragmental elevation showing one end of the tool 35 in operation; and Figure 4 is a fragmental elevation showing the other end of the tool in operation.

The tool forming the subject matter of this application comprises a body 1 in the form of a bar, one end of which is thinned and curved to form a hook 2, the bill of the hook terminating adjacent to the longitudinal axis of the body 1 to form a shoulder 4 on the end of the body 1, outwardly of the end of the bill 3 as shown in Figure 1, the throat 5 of the hook being disposed at an acute angle to the axis of the body 1 and comprising parallel inner walls 6.

In Figure 4, the numeral 7 denotes a rim having a bead 8 which has been bent inwardly too far toward the rim 7. The edge of the bead 8 is engaged in the throat 5 of the hook 2 and the bead 8, obviously may be bent out readily into the proper position shown in

dotted line in Figure 4. Because the bill 3 of the hook terminates adjacent to the axis of the body 1, the shoulder 4 constitutes a means whereby the bead 8 may be guided into the throat 5, the parallel inner walls 6 of the hook 2 receiving the bead 8 closely. 60

The opposite end of the body 1 is thinned and prolonged to form an anvil 9 which is outwardly extended and is disposed at an angle of approximately 115° with respect to the body 1, the outer end of the anvil 9 being 65 rounded as at 10, and there being a rounded heel or fulcrum 11 at the point of juncture between the anvil 9 and the body 1.

In Figure 3 there appears a rim 12 having a bead 14 which is bent outwardly beyond its 70 normal position. The rounded end 10 of the anvil 9 may be placed within the bead 14 the heel or fulcrum 11 resting against the rim 12. Then, through the instrumentality of a hammer 15, the bead 14 may be shaped 75 properly over the rounded end 10 of the anvil 9, it being observed that the anvil is tapered as at 16 from the body 1 toward the free end of the anvil so that the tool may be tilted on the heel 11 thereby to permit the 80 rounded end 10 of the anvil to be positioned properly within the distorted bead 14.

What is claimed is:

A rim tool comprising a body provided at one end with an anvil which tapers from the 85 body to the outer end of the anvil, the body being thinned to form the anvil, the outer end of the anvil being rounded, the anvil projecting laterally with respect to the body, the anvil being the sole lateral projection on 90 the body between said end of the body and the opposite end thereof, there being a rounded heel at the point of juncture between the body and the anvil, the anvil being located at an angle of approximately 95 115° with respect to the body, whereby, when the heel is placed against the base of a tire rim, and when the rounded outer end of the anvil is engaged within the bead of a tire rim, the body will be disposed at such an 100 angle to the base of the tire rim that an operator may conveniently hold a hammer with one hand and pound the bead over the rounded end of the anvil, and grasp the body of the tool with the other hand. 105

In testimony that I claim the foregoing as my own, I have hereto affixed my signature.

JAMES V. DUNBAR.
